UNITED STATES PATENT OFFICE.

JAMES B. FORCE, OF WASHINGTON, DISTRICT OF COLUMBIA.

TYPE-WRITER ATTACHMENT.

SPECIFICATION forming part of Letters Patent No. 627,180, dated June 20, 1899.

Application filed May 19, 1898. Serial No. 681,160. (No model.)

To all whom it may concern:

Be it known that I, JAMES B. FORCE, a citizen of the United States, residing at Washington, in the District of Columbia, have invented certain new and useful Improvements in Type-Writer Attachments; and I do hereby declare the following to be a full, clear, and exact description of the invention, such as will enable others skilled in the art to which it appertains to make and use the same.

This invention relates to an improvement in attachments for type-writers, &c.; and its objects are to provide a pointer, for use on type-writers employing either shifting or stationary carriages, which is easily applied to the machine and can be employed for locating a desired point upon the platen without reference to the scale which is usually provided and to provide means whereby tabulating and other similar work can be performed expeditiously.

To these ends the invention consists of a pointer secured to a stationary or shifting part of the type-writer, as will be hereinafter described, and projecting upward to a point above the carriage. Said pointer is formed of spring metal and is preferably adjustably secured to a base-plate suitably secured to the machine and provided with a spring which is adapted to hold the pointer in a normally vertical position. Said pointer is composed, preferably, of a lower horizontal portion pivoted within the base-plate and having a flattened upper surface, against the sides of which normally rests the retaining-spring, and upwardly-projecting portions separated by a substantially horizontal intermediate portion forming a "sight" for the purpose herein-after described. The lower of said upwardly-projecting portions is preferably flattened near the center to permit of its being forced backward under slight pressure, while the upper of said portions is so curved upon itself as to force the entire pointer rearwardly when an object is forced thereagainst.

In the accompanying drawings I have shown the preferred form of my invention.

In said drawings, Figure 1 is a side elevation showing the device applied to a type-writer. Fig. 2 is a detailed perspective view thereof. Fig. 3 is a central vertical longitudinal section of the base-plate. Fig. 4 is a cen-

tral vertical transverse section thereof. Fig. 5 is a perspective view of pointer detached. Fig. 6 is a top plan view of the base-plate. Fig. 7 is an inverted plan view thereof. Fig. 8 is a side elevation of the device as applied, showing a modified form of attachment. Fig. 9 is a plan view of the pointer in lowered position, and Fig. 10 is an enlarged section through the spring and end section of the pointer.

Referring to said figures by letters of reference, A is the base-plate of the pointer, provided along the center with hollow bearing-lugs *a*, joined by a narrow partition or strip *a'*, to each side of which is a cut-out portion *A'*, each terminating at its outer end in a shoulder *A*². Bending over strip *a'* and downward into each of said cut-out portions *A'* and upward against the shoulders *A*² is a retaining-spring *B*, as shown, for the purpose hereinafter described.

Pivoted within the bearing-lugs *a* and passing over strip *a'* and under spring *B* is the lower end portion *C* of my improved pointer. Said portion is preferably provided with a beveled end *c* to permit its ready insertion beneath the spring when in proper position. The upper surface of said lower portion *C* is flattened for the distance between the lugs, as at *C'*, forming shoulders *c'*, between which rests the spring *B*, which because of its position normally rests against the edges of said flattened portion.

The end portion *C* is bent upwardly from a point near the edge of the base-plate and is preferably flattened along the central portion, as at *D*, to permit of its being readily sprung back under slight pressure. At a desired distance above the base-plate said upwardly-projecting portion of the pointer is bent forward a suitable distance, as at *D'*, and then again projects upward and curves back upon itself, as shown at *D*².

Base-plate *A* is provided with suitable means for attaching it either directly to the type-writer or to a hinge-plate of peculiar construction and especially adapted for use on the top of a machine employing a shifting carriage. Said hinge-plate preferably consists of a substantially vertical arm *E*, adapted to be suitably secured at one end to the shifting guide-bar *X* and hinged at the other

end to a plate E', resting at all times upon the clips e of the hangers and traveling back and forth thereon when the carriage is shifted. If desired, however, a plate may be provided 5 whereby a smooth bearing-surface is presented to the moving hinge. By thus securing my improved pointer to a type-writer employing a shifting carriage it remains in the same relation at all times to the platen and 10 the paper thereon. If desired, however, the base-plate A may be secured directly to the frame of the machine, some forms of typewriters permitting the use of the same screws therefor which secure the clips to the casting. 15 In operation the device is secured to the machine by either of the means hereinbefore described, according to the type of the machine to which it is applied, and the forwardly-projecting portion or sight D', which extends as 20 far over the carriage and as near to the platen as possible, is adjusted to point directly above and on a line with the point of contact of the type. The carriage or platen upon being raised strikes the under side of sight D', forcing 25 the entire pointer backward until free therefrom, said pointer bending along the flattened portion D. The pointer immediately springs forward into close proximity to the platen when pressure is removed therefrom, and the carriage may be moved from 30 side to side until any desired point comes into line with the sight. The carriage can then be lowered, the front edge thereof striking the upper portion D² and again forcing the entire 35 pointer backward until the lower point of said pointer is passed, when the pointer will immediately spring back to its normal position. The type can then be struck and will hit the desired space. 40 It will be further noticed that, as shown in Fig. 2, the pointer, which projects above and over the carriage, is of great advantage in tabulating or writing in columns. By simply moving the carriage after each shift of a line 45 until the pointer "sights" the edge of the column the line can be written without any reference whatever to the scale.

If it is desired for any reason to remove the pointer from its normal position, as when a 50 cover is placed over the machine, it may be turned down upon the carriage-frame or sprung back under the guide-rod, as shown in dotted lines in Fig. 8 and in full lines in Fig. 9.

55 If it is desired to remove the pointer from the base-plate, this can be readily done by simply turning the pointer down until the shoulders c' escape the edges of spring B and then withdrawing the same from its bearings a.

In the foregoing description I have shown the preferred form of my invention; but I do

not limit myself thereto, as I am aware that modifications may be made therein without departing from the spirit or sacrificing the 65 advantages thereof, and I therefore reserve the right to make such changes as fairly fall within the scope of my invention.

Having thus fully described my invention, what I claim, and desire to secure by Letters 70 Patent, is—

1. In a type-writer attachment, the combination of a lower horizontally-projecting arm, of a pointer, and a shouldered base-plate, with a spring secured in said plate and bearing 75 upon said horizontally-projecting arm for holding the same into or out of operative position, for the purpose and substantially as described.

2. In a type-writer attachment, the combination of a base-plate, a spring attached thereto, as shown, and the horizontally-projecting arm of a pointer, said spring adapted to bear upon the upper face of said arm, substantially as described. 85

3. The combination with the platen of a type-writer carriage carrying printed matter on the paper attached thereto, of a pointer having a forwardly-projecting sight coöperating with said printed matter, substantially 90 as described.

4. A pointer for type-writers, &c., having a forwardly-projecting sight intermediate its length and provided with an upper recurved portion for guiding said pointer, substantially 95 as and for the purposes set forth.

5. A type-writer attachment consisting of a lower horizontally-projecting portion provided with a flattened upper surface, as described, a lower upwardly-projecting flattened portion, an intermediate forwardly-projecting portion or sight, and an upper recurved portion, with a base-plate, bearing-lugs upon said base-plate for the reception of said lower horizontally-projecting portion, 105 and a spring bearing upon the upper surface of said portion holding said pointer in a normally vertical position, and bearing upward against shoulders formed at each end of said base-plate, all substantially as and for the 110 purposes set forth.

6. In a type-writer attachment the combination, with a pointer and a base-plate, of a hinged plate supporting, and suitably secured to, said base-plate at one end, and, at the 115 other end, hinged to a plate secured to the shifting portion of a frame, substantially as described.

In testimony whereof I affix my signature in presence of two witnesses.

JAMES B. FORCE.
